UNITED STATES PATENT OFFICE.

EDWARD D. CHILDS, OF MILWAUKEE, WISCONSIN.

SHOE-NAILING MACHINE.

SPECIFICATION forming part of Letters Patent No. 517,027, dated March 27, 1894.

Application filed May 24, 1893. Serial No. 475,305. (No model.)

To all whom it may concern:

Be it known that I, EDWARD D. CHILDS, a citizen of the United States, and a resident of Milwaukee, in the county of Milwaukee, and in the State of Wisconsin, have invented certain new and useful Improvements in Shoe-Nailing Machines; and I do hereby declare that the following is a full, clear, and exact description thereof.

10 My invention relates to new and useful improvements in shoe-nailing machines, and consists in the matters hereinafter described and pointed out in the appended claims.

In the accompanying drawings illustrating 15 my invention: Figure 1 is a side elevation of my improved machine. Fig. 2 is a central vertical sectional view of the same. Fig. 3 is an enlarged front elevation of a part of the wire feeding and cutting mechanism showing 20 portions in section on line 3—3 of Fig. 7. Fig. 4 is a horizontal sectional view taken on line 4—4 of Fig. 3. Fig. 5 is a horizontal detail sectional view taken on line 5—5 of Fig. 7. Fig. 6 is a similar view taken on line 6—6 25 of Fig. 7. Fig. 7 is a vertical sectional view of a portion of the wire feeding mechanism. Fig. 8 is a detail side elevation of one of the supports for the wire feeding rolls. Fig. 9 is a detail sectional view of one of the wire cutting jaws taken on line 9—9 of Fig. 11. Fig. 10 is a view partly in plan and partly in horizontal section, of the devices for throwing the wire feeding mechanism into and out of operation. Fig. 11 is a front elevation showing 35 parts broken away, of the wire cutting mechanism and the lever for actuating the same. Fig. 12 is a vertical sectional view of the same taken on line 12—12 of Fig. 11. Fig. 13 is a detail cross sectional view of the mechanism 40 for producing a vertical reciprocation of the machine head. Fig. 14 is a detail view of the device for actuating the wire cutting jaws. Fig. 15 is a partly broken plan view of the mechanism for feeding the work forward, and 45 regulating the space between the nails. Fig. 16 is a detail view of a part thereof partly in section on the line 16—16 of Fig. 17. Fig. 17 is a vertical section on the line 17—17 of Fig. 15. Fig. 18 is a transverse section on the 50 line 18—18 of Fig. 15.

Referring by letter to said drawings, A designates the main standard or post, upon which

the operating mechanism is supported, B, the usual horn or anvil for supporting the work, which horn is revolubly supported upon suitable forwardly extending brackets B' B'', the latter of which is conveniently provided with an adjustable step b' for the vertical shaft or spindle b of said horn.

C represents the drive pulley which is journaled loosely upon the outer end of a stud shaft c extending horizontally from one side of the standard A, and C' a second wheel also loosely journaled upon said shaft and adapted to actuate the machine. A hand lever D is 65 arranged upon one side of the standard A and is secured at its lower end to a transverse shaft d provided with a rock-arm D' which latter engages with an eye d' in the inner end of a rod d² arranged to slide longitudinally in a central bore in the stud shaft c. The outer end of this rod is secured to a movable block d³ which engages at its outer end with a cap D² upon the outer end of the hub of pulley C, and at its inner end, engages 70 with an annular interior flange in the end of said hub.

The drive pulley C has a beveled face c' adapted for engagement with a similarly beveled face c² upon the pulley C', whereby when 80 said faces are in engagement with each other, motion will be transmitted from the pulley C to the pulley C' to drive the machine. By a movement of the lever D in one direction, the rod d² will be thrust outwardly so as to crowd 85 the drive pulley C away from the pulley C', a reverse motion of the lever obviously serving to press said pulley against pulley C'. In this manner, the drive wheel may be thrown 90 into or out of engagement with the pulley C' which operates the belt to drive the moving parts of the machine, so as to start or stop the machine in an obvious manner.

A vertically disposed rod or bar E is pivotally engaged at its lower end, as at e, with 95 the inner end of a foot lever E' which is pivoted to the standard A, at e', and is provided with the usual foot piece e², and at its upper end said rod or bar E is provided with a suitable step for a revoluble vertically disposed 100 shaft F, as in Fig. 2 of the drawings. This shaft is screw-threaded for a portion of its length as at f, for engagement with a suitable nut F', which rests upon a suitable support

within the standard A, and a spring f' carrying a dog or pawl f^2 is arranged at one side of said support so as to normally press said dog f^2 into engagement with the periphery 5 of said nut, which is provided with a series of teeth or serrations as shown more particularly in Fig. 13 of the drawings. A cam F^2 is carried by the shaft F, above the nut F' and is arranged to intermittently press the 10 spring f' outward to free the nut from engagement with the pawl or dog f^2 and to permit said spring to drop back so as to bring said pawl into engagement with the toothed periphery of the nut. The construction and arrangement of these parts are substantially the 15 same as that described in the United States Patent No. 479,784, granted to me on August 2, 1892, and the alternate engagement and disengagement of the nut by said pawl, serves 20 to produce a succession of up and down movements of said shaft F and the parts of the machine carried thereby. Upon the lower side of the machine head, I provide a suitable downwardly extending stud f^3 for engagement 25 with the end of the spring f' to disengage the pawl f^2 when the machine head is at its lowest point and no work is in the machine, so as to prevent the head from being lifted and permitted to drop or pound upon 30 the standard as would be the case were the spring pawl to remain in engagement with the nut.

Upon the upper end of the shaft F, is secured a gear G^5 which meshes with and is 35 actuated by a gear G upon the lower end of a vertical shaft g journaled in the machine head and upon the upper end of which is secured a bevel pinion G' meshing with a bevel gear G^2 upon a horizontally disposed shaft g' 40 also journaled in the head and carrying, at its other end, a suitable worm wheel H actuated by a worm h upon a vertical shaft or spindle H' which carries upon its upper end a suitable holder or reel h' for wire, and is provided 45 with a longitudinal bore h^2 for the passage of the wire to the feeding devices.

Upon the horizontal shaft g' are arranged two cam wheels G^3 and G^4 respectively, adapted for engagement with the feed actuating lever, and the lever which actuates the wire cutting mechanism.

Upon the lower end of the shaft or spindle H' is secured a carrier H^2 within which the rolls which grip and advance the wire, are 55 supported. This carrier may be secured in any desired manner to the spindle H', but is conveniently detachably engaged with the lower end thereof in the manner shown in Fig. 3, of the drawings, in which said carrier 60 is shown as provided with a screw-threaded socket engaging with the correspondingly threaded end of said spindle. A rotary head I is also secured to the said spindle and carries two gear wheels i which are fast upon

65 the upper ends of revoluble shafts I' I' arranged to extend downwardly through lateral bearing lugs i^2 on opposite sides of the car-

rier H^2 and provided at their lower ends with worms i^2 i^2 .

Transversely arranged feed rollers J J, are 70 journaled in the carrier H^2 and having projecting spindles or axes j j carrying at their outer ends suitable worm wheels J' J' which are arranged to mesh with the worms i^2 i^2 on the shafts I' I'. A sleeve K is arranged upon 75 the outside of the spindle H' and is provided with a gear k at its lower end, arranged to mesh with the gears i i as shown more particularly in Fig. 4. Around the upper end of this sleeve is arranged a flexible strap L, which 80 is secured at one end to the machine head, as at l and is arranged to engage at times with said sleeve in the manner to be presently described, to hold said sleeve from rotation.

A rotary motion is imparted to the spindle 85 or shaft H' by means of a pulley H³ which is keyed, screwed, or otherwise secured to the upper end of said spindle and around which the usual drive belt is trained, said belt being trained over the pulley C' and idlers C² 90 C² and by the engagement of the worm h with the wheel H on shaft g' a continuous rotation is imparted to said shaft and the cams G³ G⁴ carried thereby, so long as the pulley H³ and spindle H' continue to rotate. 95 Pivoted upon a bracket m at the side of the machine head, is a lever M, provided at its upper end with a roller m' arranged to rest against the face of the cam G³ as shown more particularly in Figs. 3 and 11, and this lever 100 has an operative connection with the free end of the friction band L consisting of rod m², spring m³ and nut m⁴ so as to pull said end outwardly whenever the upper end of the lever M is crowded outward by a rise in the 105 face of the cam G³. The friction band or strap L is arranged to normally grip the upper end of the sleeve K by its own resiliency, and when free to so grip said sleeve, operates to hold the sleeve from rotation, thus serving to 110 hold the gear k upon its lower end stationary. It follows from this construction, that when the said sleeve and gear are held from rotation, the rotary movement of the spindle H' with the head I and the carrier H² serves to carry 115 the gears i i around the gear k so as to produce an independent rotation of said gears i i upon their own axes in an obvious manner, and this rotation of said gears serves to actuate the worms i^2 i^2 and worm wheels J' J' to 120 rotate the wire feed rollers J J to advance the strand of wire engaged thereby, but when said friction band or strap is drawn open by the described outward movement of the lever M, said sleeve K and gear k will be free to 125 rotate with the spindle H' as the head and gears thereon are carried around thereby, so that, at such times the feed rolls will be out of operation.

The cam G³ may be provided with any desired number of rises and intermediate depressions, and is of the same general construction shown in the prior patent previously mentioned, these alternate rises and

depressions being made tapering from front to back of the cam, and the cam operatively connected with a longitudinally movable sleeve g^2 having rack teeth for engagement 5 with a revoluble pinion g^3 having operative connection by means of a crank g^4 with a rod g^5 secured to the top a' of casting A' at its lower end, and by this arrangement the cam G^3 is automatically adjusted upon the shaft 10 g' by a change of elevation of the head, so as to regulate the length of nails formed in the same manner as described in my aforesaid prior patent.

If desired, a suitable spring L^2 adjustable 15 as to tension by a screw L^3 may be arranged to engage with the arm L' of the friction band L to press the free end thereof inward and cause the said band to more firmly grip the sleeve K as desired. I also prefer to provide 20 a rod N , revolvably supported in journals upon the side of the machine head, and provided with an eccentric stud n arranged to engage with the free end of the arm L' as shown more particularly in Figs. 1 and 10, 25 and further provided with an operating lever handle n' . By a rotation of this rod N so as to bring the eccentric stud n outward, the arm L' may be pressed outwardly so as to free the sleeve K from engagement with 30 the friction band L , and in this condition the said friction device and the feeding mechanism will remain unaffected by the movements of the lever M , and consequently the feeding mechanism will be held from operation. 35 When the said rod is turned back into the position shown in Fig. 10 of the drawings, however, the arm L' is free to spring in so as to cause the friction device to come into operative engagement with the upper end of the 40 sleeve K , as before described.

The cutting mechanism for severing the wire after it is inserted in the sole of the shoe, comprises a pair of jaws O each provided with a cutting blade o and said jaws being 45 pivoted, as shown at o' , to a suitable supporting stud. Each of these jaws is provided with an upwardly extending lever arm O' , and these arms are arranged to extend upwardly adjacent to each other as shown in Fig. 11, 50 and are provided in their upper ends with depressions o^2 o^3 for the reception of an elliptical or oval stud P on the end of the shaft p of a partially toothed gear or pinion P' which is mounted in suitable bearings in the head 55 of the machine. A spring O^2 is secured to the machine head by a screw O^3 , as shown in Figs. 11 and 12, and is provided with downwardly extending arms O^3 O^4 , having inner upward extensions O^4 O^4 , arranged to engage 60 with the upper ends of the arms O' O' to press them together against said stud P . A lever Q is pivoted to the machine head as at q , and is provided at its upper end with a roller q' arranged to engage with the cam G^4 65 and at its lower end has a segmental gear q^2 engaging with the pinion P' . The spring arms O^3 O^4 normally press the arms O' O' of

the cutting jaws together, thus keeping the cutting edges apart in an obvious manner, but when the roller q' on the upper end of lever Q is engaged by a rise in the face of cam G^4 , said lever will be rocked on its pivotal support q , so as to partially rotate the pinion P' and the stud P to spread the arms O' and cause the cutting edges of the jaws O to engage with the wire to sever the same. 75

As a further and separate improvement, I prefer to arrange the feed rollers J so as to be adjustable to regulate their pressure upon the wire passing between them, and to this 80 end, I journal said rollers in bearings r in the lower ends of plates R which are secured to opposite sides of the carrier H^2 . The upper ends of these plates are arranged to engage with the sides of the said carrier in 85 the manner shown in Fig. 7 (at r' r') of the drawings, and are provided with suitable apertures through which adjusting screws R' R' are passed and which engage with threaded apertures in said carrier. By tightening 90 said screws, the plates R may be adjusted so as to press their lower ends inwardly to crowd the rolls J together upon the wire in an obvious manner.

A spring Q' is secured to the machine head, 95 and exerts its pressure against the described lever Q , as shown in Figs. 3 and 11, to keep said lever against the cam G^4 , and aid in the rotation of the pinion P' .

The mechanism for feeding the work forward, and regulating the space between the 100 nails is best shown in the detail views, Figs. 15 to 18, inclusive.

As in my prior patent, hereinbefore referred to, the upper part of the standard A 105 consists of a hollow casting A' having an upper horizontal extension a' , for the support of the upper portion a^2 of the machine-head-raising-sleeve A^2 (which sleeve is secured within the casting A' by a feather, not shown, 110 so as to freely reciprocate vertically, but be incapable of any rotary movement).

The top of the head-raising-sleeve A^2 is provided with a groove a of circular outline having a lateral continuation extending to 115 one edge of the portion a^2 , as best shown in Figs. 15 and 17, and up through the center of the circular part of said groove the hereinbefore described shaft F passes, and to this shaft, within said groove, is secured by a key 120 f^4 a horizontal cam-disk S , the top of which disk S is flush with the top and extension a^2 of the head-raising sleeve A^2 , and the under side of which disk is provided with a cam-groove s . In the bottom of the groove a there 125 is cut an arc-shaped slot a^3 for engagement with a pin t projecting from the under side of the inner end of the feed-gage T which rests in and projects out from the described lateral continuation of the groove a . This 130 gage T is provided with a vertical longitudinal slot t' therethrough in about the center of its length, and beyond this with a longitudinal recess t^2 , open to the outer end of said

gage, to receive the adjustable feed-point U, whose outer projecting end is provided with teeth u u , and one edge of which is formed with rack-teeth, as shown at u' , for regulating the degree of projection of said part U beyond the edge of the part T, by means of the lever V pivoted as shown at v to an extension t^3 of the part T, and having a sector-shaped head V' provided with teeth v' for engagement with said rack-teeth.

W is an arm provided with a longitudinal slot w through which it is adjustably secured to the under side of the extension a^2 of head-raising sleeve A² by a screw w' , said arm resting in a slot a^4 to prevent lateral movement, and having at its outer free end an upward projecting pivot-pin w^2 for engagement within the described slot t' of the gage T.

It follows, from the foregoing description of the construction of the gage and adjacent connecting mechanism, that the work placed upon the horn or anvil B is fed laterally by the movement of the described gage, as the cam-disk is actuated by the shaft F, and every time the head lifts in the manner already described, the work is fed so as to bring a fresh point beneath the nailing mechanism, the distance between the nails being regulated by the adjustment of the arm W and its pivot w^2 in or out from the inner end of the gage T, to vary the throw at the outer end of said gage, and the distance from the edge of the work to the nailing line being regulated by means of the projection of the part U, adjusted by the described lever V.

The operation of my improved machine is, in general, the same as that described in my said prior patent, with the exception of the described differences in the operation of the wire feeding mechanism and the devices for effecting an intermittent operation of the same, and the described differences in the construction and operation of the wire cutting devices, and by the gage and work-feeding mechanism.

Having thus described my invention, what I claim as new, and desire to secure by Letters Patent, is—

1. The combination with the vertically movable head of a shoe-nailing machine, of a vertically disposed revoluble shaft journaled in the head, suitable wire-feeding mechanism carried by said shaft, a gear for actuating the wire-feeding mechanism, a suitable friction device for holding said gear from rotation and suitable means actuated by the driving mechanism for alternately throwing said friction device into and out of engagement with said gear, substantially as set forth.

2. In a shoe-nailing machine, the combination with the movable head, of a horizontal shaft revolubly journaled therein and carrying a cam, a vertically disposed shaft also journaled in said head and carrying suitable wire-feeding mechanism, a sleeve loose upon said vertical shaft and provided at its lower end with a gear for actuating said wire-feed-

ing mechanism, a friction device for engagement with said sleeve, and a lever operatively engaged with said cam for alternately moving said friction device into and out of engagement with said sleeve, substantially as set forth.

3. In a shoe-nailing machine, the combination with the movable head, of a horizontal shaft revolubly journaled therein and carrying a cam, a vertically disposed shaft also journaled in said head and carrying suitable wire-feeding mechanism, a sleeve loose upon said vertical shaft and provided at its lower end with a gear for actuating said wire-feeding mechanism, a friction band arranged to embrace said sleeve, an arm operatively engaged with said band, and a pivoted lever having operative engagement with said arm and engaged at one end with said cam to produce alternate inward and outward movements of said arm to cause the friction band to alternately grip and free said sleeve, substantially as set forth.

4. In a shoe-nailing machine, the combination with the movable head, of a horizontal shaft revolubly journaled therein and carrying a cam, a vertically disposed shaft also journaled in said head and carrying suitable wire-feeding mechanism, a sleeve loose upon said vertical shaft and provided at its lower end with a gear for actuating said wire-feeding mechanism, a friction band arranged to embrace said sleeve, an arm operatively engaged with said band, a pivoted lever having operative engagement with said arm and engaged at one end with said cam to produce alternate inward and outward movements of said arm to cause the friction band to alternately grip and free said sleeve, and suitable means under the control of the operator for securing said arm at the limit of its outward movement, to permit the sleeve and its gear to run freely within said friction band, substantially as set forth.

5. In a shoe-nailing machine, the combination with the machine head and wire-feeding mechanism carried thereby, of suitable jaws pivotally engaged at their lower ends with the machine head and carrying cutting edges arranged upon opposite sides of the path of the wire adjacent to the pivotal point of said jaws, lever arms extending from the pivotal support of said jaws, a revoluble shaft, journaled in said head and provided with an eccentric or elliptical stud extending between the upper ends of said lever arms, a pinion on said shaft, and a pivoted lever operatively engaged at one end with the operating mechanism, and carrying at its other end a segmental gear meshing with said pinion, substantially as set forth.

6. In a shoe-nailing machine, the combination with a suitable support for the work, a vertically movable revoluble shaft, and a machine-head-raising sleeve vertically movable therewith, said sleeve being provided with a groove in its top surface, of a cam-

disk fast on said shaft and located in said groove and provided with a cam-groove in one of its faces, and a feed-gage also located in, and projecting from, said sleeve-groove, 5 and in operative engagement with said cam-groove, and with an adjustable pivot, for feeding the work forward, and regulating the distance between the nails, substantially as set forth.

10 7. In a shoe-nailing machine, the combination with a suitable support for the work, a vertically movable revoluble shaft, and a machine-head-raising sleeve vertically movable therewith, said sleeve being provided 15 with a groove in its top surface, of a cam-disk fast on said shaft and located in said

groove and provided with a cam-groove in one of its faces, a feed-gage also located in, and projecting from, said sleeve-groove, and in operative engagement with said cam-groove, 20 and an adjustable feed-point carried by said gage for regulating the distance between the edge of the work and the nailing line, substantially as set forth.

In testimony that I claim the foregoing I 25 have hereunto set my hand, at Milwaukee, in the county of Milwaukee and State of Wisconsin, in the presence of two witnesses.

EDWARD D. CHILDS.

Witnesses:
